DISPLAY DEVICE

Fletcher Samuel Johnson, London, England

Application December 16, 1947, Serial No. 792,049
In Great Britain December 16, 1946

2 Claims. (Cl. 211—13)

1

The invention relates to a display device and has for its object to afford simple means whereby one or more articles can readily be arranged in a variety of display positions contiguous to advertising, instructive or other literary matter relating to the article or articles displayed.

The display device according to the invention comprises a frame or board having a plurality of supports for a plurality of movable pegs or the like constituting supports for articles to be displayed or an anchorage for a support, in combination with a screen applied or adapted to be applied to a face of the frame or board, the said screen having at least one perforation through which one of the pegs or the like can protrude.

In order that the invention may be more readily understood and carried into effect, reference is now made to the accompanying drawings in which:

Figure 1 is a front view, partly broken away, of one form of the display device according to the invention;

Figure 2 is a vertical section taken on the line II—II of Figure 1;

Figure 3 is a perspective view to an enlarged scale illustrating part of the frame and of one of the shelves with pegs used in the construction according to Figures 1 and 2;

Figure 4 is a perspective view from below illustrating a platform for use with the pegs;

Figure 5 is a fragmentary perspective view of a modified form of shelf, pegs and screen;

Figure 6 is a sectional view on the line VI—VI of Figure 5;

Figure 7 is a sectional view on the line VII—VII of Figure 5.

The construction of display device according to Figures 1 to 3 consists of a rectangular frame made up of side frame members 1 and upper and lower frame members 2 and 3 of wood or synthetic resinous material, the lower frame member 3 being fitted with legs 4 so that the frame will stand vertically. The inner faces of the side frame members 1 are provided with a plurality of spaced horizontally extending grooves 5, each groove in one of the members lying opposite a groove in the other member.

The grooves 5 provide supports for shelves 6 which, for the purpose, have their ends formed with tongues 7 adapted to engage in the grooves, sufficient tolerance being allowed to enable the shelves to be withdrawn from the frame and then engaged with any selected pair of oppositely disposed grooves in the side members. In the

embodiment illustrated there are shown, by way of example, sixteen pairs of grooves 5 and four shelves 6.

In the figures now being described the shelves 5 are shown as constituted by solid boards of wood or synthetic resinous material. In the upper face of each shelf there is provided a plurality of channels 8 extending at right-angles to the front and rear faces of the frame comprised by the members 1, 2 and 3. These channels form seats for pegs 9 which are of circular cross-section and are slidable along the channels so that one of their ends can project from the front face of the frame, the pegs being held in the channels by arched strips 10 secured to the shelf. To limit their forward movement, the rearward ends of the pegs may be provided with stop-pins 11 adapted to engage against the edge of the adjacent strip 10. The frame is provided with a back panel 4a which is removable to permit adjustment in the positioning of the shelves and of the pegs.

In Figure 3 the channels 8 are shown to be of V-shape in cross-section. They may, however, be of other sectional shape such as part-circular or rectangular. In the latter event, the pegs may also be of rectangular cross-section.

Cross-partitions 12 are provided in the frame above and below the grooves 5 and spaced from the upper and lower frame members 2 and 3, thereby forming compartments in which are arranged rollers 13 upon which a screen 14 of flexible material is wound. The screen passes from one roller, over the front face of the frame, to the other roller. The compartments may contain guide rollers 15 which bear against the screen to ensure that it will lie close against the front face of the frame. One end of each of the rollers 13 extends through a side member 1 of the frame and is fitted with a milled knob 16 to facilitate rotation of the rollers in either direction.

The screen 14 is provided with a plurality of round holes 17 of a diameter slightly larger than that of the pegs 9, the holes being so positioned on the exposed section of the screen that all of them can be brought into register with the channels 8 in the shelves 6 by a suitable choice of the position of the shelves in the frame. Usually the section of the screen for the time being exposed, will have only so many holes as are necessary for the passage of the number of pegs requisite for supporting the particular number of articles to be displayed at the front of the frame. When the shelves are arranged so that certain

of the channels 8 therein lie in register with all the holes provided in the exposed face of the screen 14, the pegs can be pushed forward so as to enter the holes and project from the front face of the screen, the exposed parts of the pegs acting directly as supports or anchorages for the articles to be displayed or as anchorages for supports for the articles according to the nature of the latter.

Figure 4 shows a support adapted for cooperation with any two adjacent exposed parts of the pegs. The support consists of a platform 18 having on its underface a pair of spring clips 19 adapted for engagement of the exposed ends of the pegs.

The parts of the screen 14 not covered by the displayed articles may bear literary matter relating to the articles.

Figures 5, 6 and 7 show a shelf 6 made of sheet metal, the longitudinal edges of the shelf being bent to form downwardly extending flanges 6c, 6d, while the ends of the shelf are extended to form tongues 6e for engagement in the grooves 5 of the frame. In this case the pegs are designated 9a and are made from lengths of metal wire bent to U-shape, each peg extending through an elongated slot 20 in the flange 6d so that it can be projected inwardly and outwardly of the shelf. When projected, the pegs pass through elongated openings 17a in the screen, these openings being provided in place of the round holes 17 previously mentioned.

To limit the extent to which the pegs 9a may project from the exposed face of the screen, the free ends of the legs of the pegs are bent outwardly to form stops 9b. In Figure 5 the stops are adapted to engage with the rear face of the flange 6d. In Figures 6 and 7 the pegs are made longer than in Figure 5 and the extent of their forward movement is limited by the provision of projections 21 formed by bending downwardly portions of the metal of the shelf.

The possibility presents itself of combining in one frame shelves and pegs like those described with reference to Figures 1 to 3, with shelves and pegs like those described with reference to Figures 5 to 7. In this event the screen 14 will have round holes 17 as well as elongated openings 17a.

By having a screen mounted on winding roll 50

ers as described, or by providing a series of separate screens, it is possible to display various brands or types of articles with literature appropriate to each. Moreover the position of the holes or openings in the screen or screens can be chosen to suit the form of the articles to be displayed, while always ensuring that these holes can be brought into register with the channels in the shelves to permit passage of the pegs used in supporting the articles.

I claim:

1. A display device comprising a frame, a plurality of shelves removably mounted in said frame, a plurality of pegs mounted transversely

15 of said shelves, guide means on said shelves for maintaining said pegs in spaced relation along the shelves and permitting displacement of the pegs to project beyond the front edge of the shelves, a vertically movable screen mounted against the said front edge of the shelves, said screen having perforations which can be aligned with certain of said pegs, and can receive the aligned pegs therethrough, the ends of the pegs which protrude through said perforations forming supports at the exposed face of the screen.

2. A display device as claimed in claim 1, wherein the guide means comprises an arched strip extending along, and secured to, each of said shelves, the pegs being slidingly engaged 30 within the arches formed by said strip.

FLETCHER SAMUEL JOHNSON.
